UNITED STATES PATENT OFFICE

CLARENCE T. FAIRBANKS, OF CHICAGO, ILLINOIS, ASSIGNOR TO EDWARD & DEUTSCH LITHOGRAPHING COMPANY, OF CHICAGO, ILLINOIS, A CORPORATION OF ILLINOIS

ADVERTISING SIGN

Application filed April 16, 1932. Serial No. 605,559.

The present invention relates to an improvement in advertising signs and their construction.

The primary object of the present invention is to provide in improved form an advertising sign, or signs, which comprises a plurality of individual separable portions capable of engagement with each other in such a manner as to produce a chain of signs 10 of any desired length, with further provision for the replacement of one or more of the individual sign components so that the same may be varied, by the person using the same, without complications, the use of tools and 15 the like. This interchangeability is brought about by the particular arrangement of slots, within the sign and sign portions, which cooperate with suitable tabs and projections formed integrally with the sign and sign 20 portions.

A further object of the invention is to provide a sign-making portion of sheet material, which has tabs and projections thereon cooperating with slots in a similar sign, so that 25 the engagement and disengagement of the two or more individual sign portions with each other may be rendered most simple and at the same time sufficiently rigid for all ordinary purposes and so arranged that the 30 signs, when hooked together to form a chain, will be in accurate alignment so as to present a pleasing and attractive appearance.

A further object of the invention is to provide individual, flat sign portions containing 35 printed indicia, together with a space upon which there may be placed, by the user, further indicia such as prices, etc., the entire device being so coordinated as to produce a unitary effect.

40 For a better understanding of the present invention, it has been illustrated in the drawing appended hereto, in which drawing—

Figure 1 is a front view of the sign, showing a main portion 10 and two intermediate 45 portions 11, respectively;

Fig. 2 shows, on an enlarged scale, one of the details of construction, being a front view;

Fig. 3 is a perspective view of the reverse 50 side of the sign, also, on an enlarged scale,

showing the cooperation of various portions of the sign;

Fig. 4 is a section along the line 4—4 of Fig. 1; and

Fig. 5 shows a modification of the construction shown in Fig. 2, also on an enlarged scale.

The essential feature which characterizes the present construction lies in the provision of individual sections having means thereon which are capable of engaging slots in a main or upper portion of the aggregated sign, and tabs formed integrally with the intermediate portions and having lateral projections thereon which preferably are rounded at one point but cut straight at another, as will be more clearly described hereinbelow.

Referring now to the figures of the drawing, it will be seen that the device consists of a main display portion 10 which may have suitable advertising indicia 12 printed thereon, provision also being made, as at 13, for suspending the sign from a suitable nail or hook 14. At the lower part of the main portion 10 there are provided two slots 15 of a length sufficient to permit of the introduction of two tabs 16 with their laterally projecting nose-like portions 17. It should be noted that the said slots 15 are of a length ample comfortably to pass the greatest width of the tabs 16 with their noses 17. It should also be noticed that when used, the vertical edges 16' of the tabs 16 will lie immediately below the ends 15' of the slots 15. Each of the intermediate portions 11 is provided with two tabs 16, namely one on each edge 75 thereof, the noses 17 thereof facing in opposite directions.

By the above arrangement, the intermediate portions 11 will be maintained in accurate vertical alignment with the main sign portion 10 and with each other, it being obvious that there can be as many of the intermediate portions 11 as may be desired. Each of these portions 11 is provided with tabs 16 and with slots 15. The construction is so that 90 when two of the tabs are inserted in the corresponding slots, there can be practically no lateral movement of the intermediate portions 11 relative to the slots, to each other, and to the main plate portion 10. In the pre- 95

ferred modification, however, in addition to the slots 15, there are provided short vertical slots 18 which are at right angles with the slots 15 and are situated at the outer terminals of the said horizontal slots 15. This presents the additional advantage that when engaging one sign portion with another, the nose 17 will tend to pry up very slightly the material immediately above the slot, whereby the nose will be guided accurately into the slot without danger of tearing the nose or enlarging the slot 15 itself. In Fig. 5, however, a device without this feature is shown, as the invention is not absolutely predicated on this construction. It will also be within the scope of the present invention to have similar vertical slots at the other end of the horizontal slots.

When putting together the various portions of the sign, the operation is substantially as follows: The intermediate plate portion 11 is grasped in one hand while, for example, the left-hand tab 16 is inserted into the corresponding slot 15. It will then be found that it is possible laterally to move the tab 16 in the slot 15, and advantage is taken of this fact by pushing the tab 16 as far to the left as possible. The intermediate plate 11 is then slightly bent out of its own plane so as to permit the other tab on the right-hand side of the sign, together with the nose thereon, to enter into the corresponding slot 15, after which the intermediate plate portion 11 is released and, because of its resiliency, returns to a flat plane, whereby the right-hand tab is driven to the extreme right of the right-hand slot 15, whereby the vertical slots 18, on both sides, come into accurate alignment with the respective outer edges 16' of the tabs 16. Inasmuch as the outer edges of the said tabs are now pressing against the material of the main sign or sign portion immediately above, the accurate vertical alignment of all of the parts of the sign is assured.

Referring to Fig. 3, which is a rear perspective view, it will be seen just how the nose 17 projects along the reverse side of the sign or sign portion 10 or 11, leaving a short portion 15" of the slot unused. It will readily be appreciated that if the slots were merely made wide enough for the insertion of the tabs 16, this could be done on only one side of the sign; and if an attempt were made to insert the other tab and nose, the sign would have to be so badly distorted as to destroy it. On the contrary, with the construction of the present invention, this difficulty is completely and successfully eliminated.

By making the tabs 16 of the same color and ornamentation as the sign proper and/or the individual sign portions, a highly attractive device is produced. However, the tabs may be of a distinctive color or design.

In order to enable the user to make such

changes as he may desire, an unprinted space 20 has been left on the individual sign portions 11, which is intended to receive a gummed sticker or its equivalent, upon which indicia such as prices may be printed.

It will be seen that there are no additional parts required and that all of the parts of the sign are made of flat sheets of material which may be cardboard, thin sheets of plastic material such as celluloid, aluminum, tinned iron, or other materials, although in its ordinary form cardboard will be found to be quite efficient. However, the invention is not at all to be limited to a cardboard construction, as aluminum signs have been found to be light and of a high degree of permanence.

While in its preferred form the sign is made with the longer slots running substantially horizontally (i. e. when the sign is hanging up) and the smaller slots running vertically, it will be within the scope of the invention to make the longer slots oblique and the vertical slots at an angle differing from a right angle. When a somewhat heavier material than cardboard is employed, the provision of a second smaller slot running at an angle to the main slot presents an added advantage, as by this means the material constituting the sign is more readily bent slightly out of the plane of the rest of the sign, thereby facilitating the introduction of the tabs into the corresponding slots.

The length of the tabs 16 is, of course, a matter of indifference and can be arranged according to the taste of the designer, but the general idea is to leave a definite open space between each of the individual portions 11 and between such portions and the name plate 10.

The device has particular utility in connection with advertising ice-cream, for display at soda fountains, but may equally well be used for other purposes, such as to show the destination of trains at train terminals and the like.

What it is desired to protect by United States Letters Patent is expressed in the claims appended hereunto.

1. An advertising sign comprising the combination of a main display portion and a plurality of subsidiary portions, all made of relatively thin material, said main and subsidiary portions being provided with slots parallel to their larger axes near the lower edges thereof, means for suspending said larger portion, tabs on said subsidiary portions capable of cooperative engagement with said slots, laterally extending projections on said tabs so arranged that when the tabs are in engagement with said slots said projections will lie on the reverse side of the portions beyond the extent of said slots.

2. An advertising sign comprising the combination of a main display portion and a plurality of subsidiary portions all made of

relatively thin material, said main and subsidiary portions being provided with slots parallel to their larger axes near the lower edges thereof, means for suspending said 5 larger portion, tabs of lesser width than said slots on said subsidiary portions extending in a direction at right angles to said slots, lateral projections on said tabs of such dimensions that the combined width of said 10 projections and tabs is substantially equal to the length of said slots, whereby when said tabs are in engagement with said slots the outer edges of said tabs will lie in a vertical plane that passes through the outer termini 15 of said slots.

3. In an advertising sign of the type described in claim 1, the improvement which consists of a subsidiary sign-portion comprising a flat sheet of material provided with 20 longitudinal slots near one edge thereof, tabs integral with said sheet extending outwardly thereof from the edge opposite said slots and so positioned that the outer edges of said tabs are in alignment with the outer termini of 25 said slots, the slots being longer than the width of said tabs, lateral projections on said tabs of such size that the combined width of said projections and said tabs is substantially equal to the length of said slots.

4. In an advertising device of the type described, the combination of a main sign-plate made of thin plate-like material provided with two horizontal slots near the lower edge thereof, two vertical slots of shorter length 35 than the horizontal slots located at the extremities of the horizontal slots and making an angle therewith, means for suspending the main sign-plate, the subsidiary sign-plates having spaces for the imprinting of indicia 40 thereon and a space for the reception of an adhesive label, said subsidiary plate being likewise provided with slots entirely similar to those of the main sign-plate, vertically extending tabs at the upper edge of said 45 subsidiary plates, laterally extending projections on said tabs of such size that the combined width of the tabs plus the projections will be substantially equal to the length of the slots, whereby when the tabs and projections of the subsidiary plate are in engagement with the slots of the main plate the projections on the tabs will prevent dislodgment by a downwardly applied force, while the outer edges of the tabs will prevent any substantial lateral movement of the tabs passing 50 through said slots, whereby the main plate and subsidiary plate are kept in accurate vertical alignment.

5. In an advertising device of the type described in claim 1, the improvement which consists of subsidiary sign-portion comprising flat sheets of material provided with a plurality of cooperating slots near one edge thereof, two of said slots running substantially parallel with the longer axis of said

sheets and two of the slots being at an angle to the aforesaid slots forming corners therewith, said second slots being comparatively very short, tabs extending from said sheet at points opposite said longer slots, the tabs being of lesser width than said first-mentioned slots, and laterally extending projections on said tabs of such width that the combined dimension of said projections and tab-width is substantially equal to the length of the slots that run substantially parallel with the larger axis of said sheet.

6. In an advertising device of the type described in claim 1, the improvement which comprises a subsidiary sign-portion consisting of a sheet of flat material, projections integral with said sheet and extending from one of the longer edges thereof at right angles to said edge, said sheet being provided with two horizontal slots near the edge opposite said tabs, said slots beginning respectively on a line with the outer edges of said tabs and being longer than the width of the tabs, short supplementary slots at the end of slots running at an angle and contiguous thereto, and lateral projections at the end of said tabs.

7. An advertising sign comprising a main suspensible sign portion and subsidiary appendant sign portions, said main portion being provided with elongated slots and said subsidiary portions being provided with similar slots, upwardly projecting tabs on said subsidiary portions, and nose-like lateral projections on said tabs, said slots being sufficiently wide to admit said tabs and projections.

In witness whereof, I have hereunto subscribed my name.
